(57) **CLAIM**

The ornamental design for a tool box, as shown and described.

DESCRIPTION

FIG. 1 is a perspective view of a tool box showing my new design;

FIG. 2 is a front elevational view thereof;

FIG. 3 is a rear elevational view thereof;

FIG. 4 is a left side view thereof;

FIG. 5 is a right side view thereof;

FIG. 6 is a bottom plan view thereof;

FIG. 7 is a top plan view thereof; and

FIG. 8 is a view of the tool box of FIG. 1 showing tools inside in broken line; and,

FIG. 9 is a perspective view of the back of the tool box showing the handle in recessed position.

The broken line showing in FIG. 8 is for illustrative purposes only and forms no part of the claimed design.
